UNITED STATES PATENT OFFICE.

EDMUND N. BROWN, OF SAN FRANCISCO, CALIFORNIA, ASSIGNOR TO MAJESTIC ELECTRIC DEVELOPMENT COMPANY, A CORPORATION OF CALIFORNIA.

ELECTRIC HEATER.

1,245,084.

Specification of Letters Patent. Patented Oct. 30, 1917.

Application filed July 10, 1917. Serial No. 179,732.

To all whom it may concern:

Be it known that I, EDMUND N. BROWN, a citizen of the United States, residing at San Francisco, in the county of San Francisco and State of California, have invented certain new and useful Improvements in Electric Heaters, of which the following is a specification.

This invention relates to electric heaters in which the heat waves are generated by a resistance coil or heating unit and are then reflected from a highly polished surface.

One of the main purposes of my invention is to provide an electric heater or radiator in which the highly heated portions are inclosed by protecting members, but one readily accessible for examination or repair.

In the accompanying drawings, Figure 1 is a front elevation of an electric radiator embodying my invention; Fig. 2 is a side elevation thereof partly in section; Figs. 3, 4, 5 and 6 are detail views of certain of the parts hereinafter described.

The radiator comprises a concavo-convex reflector 1, having a highly polished inner surface, and which is secured by screws or in other suitable manner to an outer casing 3, mounted on a base 4. The heating unit consists of a resistance coil 6, wound upon a refractory tubular core or bobbin 7, supported in any suitable manner in spaced relation with the reflector 1, and preferably at the focus of its curved surface. I prefer to support the heating unit by securing the terminals of the resistance coil 6, together with reinforcing wires 8, wound around the ends of the bobbin if desired, to the standards 9, the ends of the wires being held by clamping screws 10.

In order to thoroughly insulate the standards from the metal reflector 1 and to rigidly secure them thereto, the margin of the aperture in the reflector may be flanged or struck up into an annular boss 12. Mica washers or other insulating disks 14, insulate the bolt 15, and center it in the aperture passing through the reflector plate. The bolt passes through a hole in the angle plate or standard 9 and is threaded through a threaded hole in the contact washer 16. The metal washer 16 is preferably oblong and the ends are bent up to form retaining fingers to confine the end of the conductor so that it may not contact with the metal re-

flector or adjacent objects. The conductors 55 or lead wires 18 pass through an insulating bushing 20 in the outer casing, the terminals being clamped between the nuts 17 and the contact washers 16.

The air-space 5, between the reflector 60 plate 1 and the casing 3 prevents the latter from becoming heated. In order to prevent the outer exposed edge of the heater from being heated I provide the casing with a marginal annular flange 3*.

The guard wires 23, forming a protective cage over the reflector are clamped at their converging ends between disks or plates 24, and at their outer ends are riveted into a ring 25 which fits snugly within the marginal flange of the annular portion 3*. The guard cage is hinged by bending two of the upper guard wires into eyes or loops 26, and passing them through holes in the flange. The cage may be fastened in closed position by bending the end of one of the wires into a pin 27, to pass through aligned holes 28 in the ring and flange, the parts thus constituting a spring catch.

It will be evident that various changes and modifications can be made without departing from my invention.

I claim:

1. An electric heater, comprising a concavo-convex reflector, a heating unit supported at substantially the focus of said reflector, an annular member extending outwardly from the margin of said reflector, and a protective cage having guard wires arched between opposite sides of said annular member.

2. An electric heater, comprising a concavo-convex reflector, a heating unit supported at substantially the focus of said reflector, an annular member extending outwardly from the margin of said reflector, and a protective cage of arched guard wires hinged to said annular member so that it may be swung outwardly from the reflector.

3. An electric heater, comprising a concavo-convex reflector, a heating unit supported at substantially the focus of said reflector, a concavo-convex casing extending over the convex side of said reflector and spaced therefrom except at the margins, said casing having an annular portion extending outwardly from the margin of said reflector, and a protective cage having guard

wires arched between opposite sides of said annular portion.

4. An electric heater, comprising a concavo-convex metal reflector, a heating unit in spaced relation thereto, said reflector being provided with apertures having their margins bent to form flanges, insulating

means upon either side of said flanges, and connecting devices extending through said insulating means and connected to the terminals of said heating unit.

In testimony whereof I affix my signature.

EDMUND N. BROWN.
